HIGH INTENSITY LAMP

Dan M. Andre, 8843 Kostner Terrace, Skokie, Ill. 60076

Filed Nov. 18, 1966, Ser. No. 4,737

Term of patent 3½ years

(Cl. D48—20)

FIG. 1 is a perspective view of a high intensity lamp illustrating my new design;

FIG. 2 is a front elevational view of the same;

FIG. 3 is a top plan view of the same; and

FIG. 4 is a fragmentary rear elevational view of the base of the said lamp.

FIG. 5 is a fragmentary side elevation of the base of the lamp.

The dominant features of my design reside in the portions shown in full lines. The support arm has been fragmentarily shown in FIGURES 3, 4 and 5 for convenience of illustration.

I claim:

The ornamental design for a high intensity lamp, substantially as shown and described.
